UNITED STATES PATENT OFFICE

GEORGE POLL, SR., OF NEW YORK, N. Y.

INFANT INCUBATOR

Application filed May 19, 1930. Serial No. 453,806.

This invention relates to an infant incubator for cradling and nurturing an infant from birth until a time when it reaches an age where such a device is no longer required, ⁵ the device being designed for normal as well as premature or marasmic infants.

The invention broadly aims to provide an improved portable infant incubator including a casing or housing having an open upper end within which a crib, basket or equivalent receptacle for the infant is supported, together with means for heating, humidifying and circulating air through the casing or housing and around and over the crib or receptacle to maintain the air supplied to the infant at the proper temperature and in the proper condition, and this without insulating the infant from the natural environment with which it must be later surrounded.

The invention further resides in the provision of means for supporting the crib in a horizontal position or limited various tilted positions, with which supporting means the crib is detachably associated to permit of its complete removal from the casing or housing when desired.

The invention further comprehends in an infant incubator, means for heating and controlling the temperature, together with means for regulating the circulation of air therethrough, in addition to means for humidifying the air to replace the natural moisture dispelled by the heating of the air.

Other objects of the invention reside in the provision of an improved incubator for infants which is comparatively simple in its construction and mode of use, inexpensive to produce and maintain and which is highly efficient in its purpose.

With the above recited and other objects in view, reference is had to the following description and accompanying drawings, in which there are exhibited several examples or embodiments of the invention, while the claims define the actual scope of the same.

In the drawings:

Figure 1 is a perspective view of an infant incubator constructed in accordance with the invention.

Figure 2 is a top plan view thereof.

Figure 3 is a longitudinal vertical sectional view therethrough taken approximately on the line indicated at 3-3 in Figure 2.

Figure 4 is a transverse vertical sectional view taken approximately on the line indicated at 4-4 in Figure 3.

Figure 5 is a plan view on a reduced scale illustrating a modified form of the crib supporting and tilting means.

Figure 6 is a fragmentary vertical sectional view therethrough taken approximately on the line 6-6 of Figure 5.

Referring to the drawings by characters of reference, the incubator includes a casing or housing which is designated generally by the reference character A, and which casing or housing includes a bottom wall 10 having marginal upstanding side and end walls 11 and 12, the top or upper end of the casing or housing A being open. The casing or housing is supported in any suitable manner and, as illustrated, the supporting means consists of depending corner legs 13 which are preferably provided with castors 14 to render the incubator portable. A crib, basket or other receptacle for the infant is designated generally by the reference character B, and the same is supported within the upper open end of the casing or housing A in spaced relation to the side and end walls. Preferably, the crib or basket is removably mounted on a tiltable supporting frame designated generally by the reference character C, the center cross rail 16 of which is connected by a hinge 17 to a cross bar 18, the opposite ends 19 of which cross bar are riveted or otherwise attached to the opposite side walls 11 of the casing or housing A. The end rails 20 of the frame C are provided with hooks 21 which are designed to engage with the endmost cross bars 23 of the crib or basket structure B, whereby the crib or basket is detachably associated with the frame. In order to permit of limited tilting of the frame C while at the same time making provision for securing the frame in its variously tilted positions or in a horizontal position, one of the end rails 20 of the frame is pivotally connected as at 24 to a depending link 25 provided with a longitudinal slot 26. A cross rod 27 extends

through the slot 26 of the link 25, and said cross rod also extends through an opening or aperture 28 in one of the side walls 11 of the casing or housing A, with a headed end 29 disposed exteriorly of the side wall. The opposite end 30 of the rod 27 is threaded and protrudes through an opening or aperture 31 in the opposite side wall and receives thereover a washer 32 and a nut 33 having an interiorly threaded bore 34 and radially projecting manipulating handles 35. Washers 36 are disposed on opposite sides of the link 25 and are positioned on the cross rod 27, while sleeves 37 are positioned on the rod 27 and interposed between each washer and the inner surface of the side walls 11 respectively. The upper end of the slot 26 in the link 25 terminates at a point where it will engage with the rod 27 when the frame C is in a horizontal position. It will also be observed that the hinged connection 17 between the frame and the cross bar 18 is disposed at one side of the longitudinal center of the frame, preferably the side nearest to which the link 25 is attached.

From the construction of the supporting frame and its mounting, it will be apparent that the frame with the basket or crib carried thereby may be variously tilted from its horizontal position and locked or maintained in the horizontal or tilted position by tightening up the nut 33 on the threaded end 30 of the rod 27, thereby exerting an end thrust on the sleeves 37 to cause the same to be frictionally clamped respectively between the opposite side walls 11 and the washers 36 disposed on the opposite sides of the link 25. It will also be observed that the crib or basket B may be readily detached and removed by shifting the same longitudinally so that the endmost cross bars 23 of the crib or basket structure are disengaged from the hooks 21.

In order to provide means for admitting air to the interior of the casing or housing A and to promote and regulate the circulation of the air therethrough and upwardly around and over the crib or basket B, vent openings 40 are formed in the bottom wall 10 of the casing or housing, and the opening and closing of the vent openings is controlled and regulated by means of slideable plates 41 formed with corresponding apertures 42, said plates being mounted in guides 43 on the under side of the bottom wall 10 and depending handles 55 being attached to the plates for effecting the shifting movement thereof.

Suitable heating means is provided within the lower end of the casing or housing A, such as a set or battery of carbon incandescent lamps 45 which are shown as arranged in sockets 46 supported by the bottom wall 10. The control of the heat within the casing or housing A is accomplished by means of a multiple switch 47 by virtue of which two,

four or six of the lamps 45 may be selectively lighted.

In order to insulate the lower part of the casing or housing A and at the same time provide a space 48 through which the wiring 49 leading to the lamps and switch 47 may be arranged, an inner marginal wall 50 is spaced from the side and end walls 11 and 12 by an upper outwardly projecting marginal flange 51, the said inner marginal wall 50 being of a height to extend from the bottom wall 10 to a point approximately halfway up the casing or housing side and end walls. This defines what may be termed the dead air space 48, while the flange 51 presents a shoulder within the casing or housing A.

Suitable humidifying means D is also provided for supplying the desired moisture to the heated air circulated through the casing or housing, and said humidifying means is in the nature of a liquid receptacle or tray 55 which is removably supported by a cradle designated generally by the reference character E, and which cradle consists of a rectangular frame 56 of angle construction in cross section attached to end cross straps 57, the upwardly extending opposite ends 58 of which are provided with outturned terminals or extremities 59 which are designed to rest upon the shoulders defined by the outturned flanges 51 of the inner marginal wall 50. Preferably, the flanges will be formed with upwardly projecting lugs 60 to maintain the cradle against longitudinal sliding movement and to cause the positioning of the cradle and the humidifying tray directly over the heating lamps 45 so that the heat from said lamps will function to cause evaporation of the water or other liquid in the tray 55 for admixture with the air circulated through the casing or housing. In order to provide means for gaining access to the casing for removing and replacing the humidifying receptacle without disturbing the infant's crib or basket, a doorway is provided in one of the side walls 11, and said doorway is normally closed by a door 65 which is hinged as at 66 to the side wall and which is provided with a suitable latch mechanism 67 for maintaining the same in closed condition. Preferably, the door is formed with a glass or other transparent panel 68 through which the lighted condition of the heating lamps may be observed without the necessity of opening the door.

In order to gauge the temperature within the casing or housing A, a support 70 for a thermometer 71 is secured to the inner side of one of the end walls 12 and a window opening 72 covered with a transparent panel 73 is provided in the end wall in alignment with the thermometer support. The casing, housing or cabinet A may be provided with a hand rail 74 adjacent the upper end of one

wall, while a chart rack 75 may also be supported by one of the end walls 12 to removably receive a chart adapted to bear various indicia. The wiring 49 may lead to a suitable socket 76 on one of the end walls 12, which socket is adapted to receive the usual plug 77 of an extension cord 78 which may be plugged into a convenient outlet for supplying current to the heating lamps.

5 In the form of the invention illustrated in Figures 5 and 6 of the drawings, a slight modification of the mounting for the basket or crib supporting frame C is disclosed. In this instance, the frame C is directly attached to a cross tube or sleeve 80 which is approximately of a length equal to the normal spacing of the side walls 81 of the casing, housing or cabinet A. A cross rod 82 having a head 83 at one end extends through 10 the side walls 81 and has its threaded end 84 provided with a nut by virtue of which the side walls 81 may be flexed inwardly and frictionally clamped against the opposite ends of the cross tube or sleeve 80. In order 15 to provide a rest for the frame C to sit against when in its normal horizontal position, an inwardly projecting lug or bracket 85 is attached to one end wall, and said lug or bracket 85 is apertured as at 86 to receive there-through an arcuate depending guide rod 87 having an offset terminal 88 which is designed 20 to engage with the under side of the lug or bracket 85 to positively limit the tilting of the frame C beyond a predetermined degree.

25 35 What is claimed is:

1. In an infant incubator, a casing or cabinet having an open upper end, a bottom wall and upstanding flexible side and end walls and means for supporting an infant's crib or 40 container within said open upper end of the casing in spaced relation to the side walls consisting of a tilttable frame and means for flexing the side walls of the cabinet to frictionally hold the crib supporting frame in its horizontal or variously tilted positions, said latter means consisting of a slotted link pivotally attached to and depending from the frame, a cross rod having a head at one end and extending through the side walls and through 45 the slot of said link, sleeves interposed between the opposite sides of the slotted link and the inner sides of the side walls of the cabinet and surrounding the cross rod and means at the other end of the cross rod for 50 manually exerting an axial thrust on the cross rod to cause the side walls to be flexed for advancing the sleeves and frictionally gripping the slotted link between said sleeves.

55 60 65 70 75 80 85 90 95 100 105 110 115 120 125 130

2. In an infant incubator, a casing or cabinet, a supporting frame for an infant's crib or container, a bar extending transversely across said casing and a connection between the said bar and the said frame between the ends of said frame and in closer relation to one end whereby to permit of and cause said

frame, when unrestrained, to normally move gravitationally from a horizontal position and means for limiting the movement of the frame to a predetermined tilted position and a horizontal position respectively, said means including a slotted member fulcrumed to and depending from the frame and a transverse stationary rod extending through said slotted member, means carried by said transverse stationary rod, for clampingly engaging said slotted member to hold the frame in its variously tilted positions and an exteriorly disposed device engaging said rod and axially movable thereon for effecting the movement of the latter means to set up said clamping engagement.

3. In an infant incubator, a casing including upstanding walls, at least one of which is flexible, a crib supported within said casing for movement from a horizontal position to a limited tilted position, means for frictionally holding said crib in its horizontal or variously tilted positions including as a part thereof, a portion of said flexible wall, said means further including a tubular element within the casing against which said wall is frictionally forced, a member extending through the tubular element and flexible wall and protruding from the casing and a device operatively engaging said protruding portion and the flexible wall respectively for flexing said wall to frictionally force the same against the tubular element.

4. In an infant incubator, a casing including upstanding walls, at least one of which is flexible, a crib supported within said casing for movement from a horizontal position to a limited tilted position, means for frictionally holding said crib in its horizontal or variously tilted positions including as a part thereof, a portion of said flexible wall, said means further including a tubular element within the casing against which said wall is frictionally forced, a rod extending through the tubular element and flexible wall and protruding from the casing, said protruding portion being threaded and a nut engaging said protruding portion and the flexible wall respectively for flexing said wall to frictionally force the same against the tubular element.
